LOUIS AUGUSTUS DRAGO, OF SEATTLE, WASHINGTON.

FUEL-CONTROLLING DEVICE.

1,075,701.

Specification of Letters Patent.

Patented Oct. 14, 1913.

Application filed October 14, 1912. Serial No. 725,639.

REISSUED

To all whom it may concern:

Be it known that I, LOUIS A. DRAGO, a citizen of the United States, and a resident of Seattle, in the county of King, State of Washington, have invented certain new and useful Improvements in Fuel-Controlling Devices, of which the following is a specification.

This invention relates to fuel controlling devices and more particularly to such devices as are adapted to be used in connection with liquid or gaseous fuel, and has for its principal object to provide a simplified form of such devices in which the feed of the fuel is automatically controlled and in which are safety devices for maintaining either a maximum or a minimum combustion.

Other objects will appear as the invention is more fully described in the following specification and shown in the accompanying drawings, in which—

Figure 1 is a central longitudinal sectional view of my device, with parts broken away. Fig. 2 is an enlarged fragmentary view, partly in section upon the line $x-x$ of Fig. 1, looking in the direction of the small arrows.

Referring now more particularly to the drawings, the reference numerals 1 and 1^a designate conducting pipes which are threaded, as shown, and to which are joined the hollow casting 2, by means of the unions 3 and 3^a, and the fittings 4. Within the union 3 is the wall 5 in which is the bypass 6 which is normally closed by the valve 7 upon the upper end of the stem 8, the said stem being upwardly pressed by the spring 9 which is seated upon the plug 10 within the lower part of the said union. The said plug has the shoulder 11 which fits snugly against the lower edge of the union and which may be suitably packed. The upper and lower ends of the said plug are threaded, as shown, and to its lower end is secured the cap 12, through which, and the said plug, slidably passes the stem 8 which extends downwardly and has its lower end threaded as shown, and to which is fitted the correspondingly threaded block 13^a. The hollow casting 2 is divided by the wall 13 into the two chambers 14 and 15. Through the said wall is an opening to admit the lower end of the pipe 16, around which may be the packing 17. The pipe 16 extends upwardly and terminates within the baffle 18 in the cap 19, which is secured to the upper

end of the larger pipe 20, whose lower end is screwed into the hollow casting 2. In the extreme upper end of the cap 19 is screwed the shell 21 which is slotted through its top at 22 to form a jet or burner for the oil or other such fuel which, when the valve 7 is open, flows through the supply pipe 1^a, thence into the chamber 14 and upwardly through the small pipe 16 and finally emerges through the baffle plate 18 and mingles with the steam which comes in through the pipe 1 and forces upwardly through the large pipe 20. Through the wall 13 is the second opening to admit the valve plug 23. The chamber 15 may be shut off from the supply pipe 1 by means of the valve plug 24, in the same manner in which the oil supply may be cut off from the chamber 14 by its valve plug 7, as will be understood. The valve plug 24 has the stem 26 which is upwardly pressed by the spring 27 and which operates in the same manner as the spring 9 on the opposite side of the device, the plug 28 being screwed into the union 3^a to close the same, and against which bears the spring 27. To the lower end of the hollow casting 2 is screwed the hollow casting 29 which is ground to fit the lower casting 30 and the two castings are screwed together by means of the screw 31, and between the said castings is the diaphragm 31^a. The casting 30 is bored through at 32 to slidably receive the stem 33 whose upper end is secured centrally to the said diaphragm. The casting 30 has the downwardly extending legs 34 which join the disk 35, the lower internal portion of which is threaded as shown, and to which is secured the cylinder 36, in which slides the disk 37 which is upwardly urged by the spring 38. The disk 35 is bored through at 39 to slidably receive the stem 33, the lower end of which bears against the disk 37. The stem 33 is threaded for a purpose presently to be explained but the apertures 39 and 32 are smooth bored. Into the lower end of the cylinder 36 is screwed the closing cap 40, through which passes the screw 41, the opening through the said cap being screw threaded to correspond to the threads of the screw, and against the upper end of the said screw bears the disk 42 which also slides within the cylinder 36. Along the lower side of the upper portion of the casting 30 are cut the racks 43. The lower end of the stem 26 is screw threaded to the block 44 and project-

ing respectively from the said block and the block 13^a is a stud 45, over which hooks one end each of the bars 46. The opposite ends of the said bars hook over the annular edge 5 of the collar 47, as clearly shown in Fig. 1, the said collar being recessed as at 48 to receive the extreme ends of the hooked portions of the said bars.

Meshing with the racks 43 are the pinion 10 wheels 49 which are joined together in pairs by the stems 50 which terminate at one of their ends in the angular stubs 51 so as to fit a key and to be turned thereby. The stems 50 contact with the upper sides of the bars 15 46. Passing through the legs 34 on one side of the device are the stems 52 which terminate in the head blocks 52^a, which normally bear against the bars 46 and are yieldingly held there by the springs 53, the upper 20 sides of the said blocks constantly bearing against the lower side of the casting 30, so as to slide freely thereunder when the inner ends of the bars 46 are depressed below the plane of the said blocks. One end of each 25 of the springs 53 bears against one of the head blocks 52^a, and the opposite ends of the springs bear against one of the legs 34. The collar 47 is screw threaded to fit the threaded portion of the stem 33, and may be 30 adjusted up or down thereon by turning the collar, and fitted to the screw threaded portion of the stem 33 are also the jam nuts 55 and 56, the latter being upwardly pressed by the relatively light spring 57. The pipe 35 58 extends from the interior of the hollow casting 29 to the steam supply pipe 1, so that when steam enters the said supply pipe it descends into the hollow casting 29 above the diaphragm 31^a and forces the same 40 downwardly against the action of the spring 38 and thrusts the stem 33 and its attached collar 47 downwardly allowing the inner ends of the bars 46 to correspondingly descend.

45 In the operation of the device the valve plugs 24 and 7 are first screwed downwardly through the block 44 and 13 respectively until the desired initial amounts of steam and oil respectively are permitted to pass 50 through the pipes 1 and 1^a into the chambers 15 and 14 respectively, the springs 9 and 27 tending always to force the said valve plugs upwardly. The stems 50 which join the pinions 49 act as fulcrums for the bars 46, 55 and the collar 47 acts as an adjustable stop for the hooked ends of the said bars. In the drawings the pinions 49 are shown equidistant from the stem 33, which allows the valve plugs 7 and 24 to stand away from 60 their respective seats an equal distance, and permits the steam to flow from the supply pipe 1 into the chamber 15 at the same rate as the oil flows from the pipe 1^a into the chamber 14, which is not always desirable.

65 It is obvious that as the steam forces the dia-

phragm 31^a downwardly the valve plugs 7 and 24 will be drawn upwardly by their respective springs 9 and 27 and that this upward movement of the said plug will be governed entirely by the positions of the pinions 49 and their stems 50 with respect to the stem 33. If less oil than steam is desired to be fed all that is necessary is to rotate the right hand pinion wheel 49 away from the stem 33, and if a greater feed of oil than steam is necessary the same pinion wheel is moved toward the stem 33. The pinion wheel upon the opposite side of the device may be moved in the same manner to affect the valve plug 24. The head blocks 52^a, already described, have the effect of automatically governing the feed so that no less than a predetermined amount of either steam or oil may be fed to the burner. The downward movement of the hooked ends of the bars 46 necessary to free the head blocks 52^a and allow them to spring over the said bars, is, of course, governed by the position of the collar 47 with respect to its stem 33. When the steam pressure becomes sufficient to cause the stem 33 and its collar 47 to move downwardly to permit the hooked ends of the bars 46 to drop below the path of the head blocks 52^a, and the same spring over the said bars, then the feed of the steam and oil will never be less than it is at that instant, until the said head blocks are manually withdrawn and the parts re-adjusted. A greater feed, however, is possible after the movement of the head blocks just referred to, but this is also automatically limited by the jam nuts 56 which may be adjusted anywhere along the stem 33. As the said jam nuts approach the limit of their downward movement the light spring 57 is gradually compressed so as not to cause a too sudden stoppage of the parts, which might strip the threads or cause other damage. The tension of the large spring 38 is adjustable by means of the screw 41, as will be understood.

While I have shown a particular form of embodiment of my invention, I am aware that many minor changes therein will readily suggest themselves to others skilled in the art, without departing from the spirit and scope of my invention. I do not therefore, desire to be limited to the exact form shown and described, except as limited in the appended claims.

Having described my invention, what I claim as new and desire to protect by Letters Patent is—

1. The combination with the steam and oil inlet valves and diaphragm of an oil burner, of a spring-pressed stem centrally connected to the diaphragm and adapted to vibrate therewith, an adjustable recessed collar upon said stem, levers connected with the said valves and adapted to hook over the

annular edge formed by the said recess, racks fixed with respect to the frame of the burner, and pinions which coöperate with the said racks and form movable fulcrums 5 for the said levers, whereby varying movements thereof are permitted as the dia- phragm is vibrated, and safety locks adapted to limit the movement of said valves.

2. The combination with the steam and 10 oil inlet valves and diaphragm of an oil burner, of a spring-pressed stem centrally connected to the diaphragm and adapted to vibrate therewith, an adjustable cupped col- 15 lar upon said stem, levers connected with said valves and adapted to hook over the

edge of the cupped portion of said collar, racks fixed with respect to the frame of the burner, pinions which coöperate with said racks and form movable fulcrums for said levers, whereby varying movements thereof 20 are permitted as the diaphragm is vibrated, and safety catches which are adapted to spring out over the said levers and lock them against retrograde movement when the said levers have completed a predeter- 25 mined travel.

LOUIS AUGUSTUS DRAGO.
